UNITED STATES PATENT OFFICE.

LEWIS W. BROWN, OF BERKLEY, VIRGINIA, ASSIGNOR OF ONE-HALF TO FRANK D. BOZARTH, OF WILLIAMSBURG, VIRGINIA.

TRANSMISSION-GEAR.

1,013,737.

Specification of Letters Patent.

Patented Jan. 2, 1912.

Application filed December 27, 1909. Serial No. 535,073.

To all whom it may concern:

Be it known that I, LEWIS W. BROWN, a citizen of the United States, residing at Berkley, in the county of Norfolk and State 5 of Virginia, have invented certain new and useful Improvements in Transmission-Gears; and I do hereby declare the following to be a full, clear, and exact description of the invention, such as will enable others 10 skilled in the art to which it appertains to make and use the same.

This invention relates to transmission gears, and has for an object to provide a friction gear for transmitting motion having improved means for varying the transmitted speed and also for reversing and varying the speed.

A further object of the invention is to provide a friction gear capable of reversing 20 in variation as above specified and also capable of transmitting motion to a shaft out of alinement with the driven shaft.

A further object of the invention is to provide improved means for throwing the 25 transmission gear out of engagement.

With these and other objects in view, the invention comprises certain novel constructions, combinations and arrangements of parts, as will be hereinafter fully described 30 and claimed.

In the drawings:—Figure 1 is a view in side elevation of the present invention shown in association with a conventional motor and propeller. Fig. 2 is a top plan 35 view of the device as shown at Fig. 1.

Like characters of reference designate corresponding parts throughout the several views.

A shaft 10 is journaled in any approved 40 manner as in the journal box 11 and is driven by any approved means as the motor shown conventionally at 12. The shaft 10 carries a friction disk 13 having its plane perpendicular to the shaft and preferably 45 held against end thrust by the journal box 11.

Spaced from the disk 13 a shaft 14 is journaled at right angles to the shaft 10 and is provided with a friction disk 15 adapted to move longitudinally upon the shaft 14 50 but held from rotary movement thereon by any usually employed means. To move the friction disk 15 slidably upon the shaft 14 a collar 16 is rigidly connected with the disk 15 and engaged by links 17 carried by a 55 lever 18. It will be apparent that as the

lever 18 is manipulated the disk 15 will be 60 slidable along upon the shaft 14 and as the disk approaches to the center of the disk 13, with which it is in frictional engagement, the speed at which the disk 15 is rotated will be decreased until upon reaching the center, rotary motion will be stopped only to be begun again in the reverse direction as the disk 15 is moved beyond the center of the disk 13 in the direction indicated 65 by the arrow. It will thus be apparent that by the simple manipulation of the single lever 18 the speed of rotation of the disk 15 may be increased, decreased or reversed.

Mounted rigidly upon the shaft 14 is a 70 disk 19 not in engagement with the disk 13 but in engagement with a disk 20 carried upon a shaft 21. As the shaft 14 rotates with the disk 15 it will be apparent that the disk 19 is rotated therewith, and that 75 when in frictional engagement with the disk 20, such disk 20 and its shaft 21 will also be rotated.

The shaft 21 is journaled in the journal 80 box 22 in which it is longitudinally slid able and is controlled by a lever 23 having a collar 24 in which such shaft rotates. The lever 24 is provided with a spring-pressed pawl 25 positioned to engage a segment 26 so that the disk 20 may be moved away from 85 the disk 19 or moved into engagement with such disk and the pressure of the disks 19 and 20 increased or decreased at will. As shown and illustrated in the drawing a shaft 21 carries a conventional propeller 27, it 90 being understood, however, that such propeller is shown only to illustrate the means of applying power, and that the utility of the device is not limited to operating a propeller but is intended to operate any mechanical parts.

What I claim is:—

1. In a transmission mechanism shafts journaled in the same plane, disks carried at the ends of the shafts and spaced apart, 100 one of said disks being of greater diameter than the other, a shaft journaled transversely between the disks, a disk carried rigidly by the transverse shaft and engaging the larger disk adjacent its periphery, 105 and a disk carried by and longitudinally movable upon the transverse shaft, such movement being diametrically upon and across the center of the smaller disk.

2. In a transmission mechanism, shafts 110

- mounted in the same plane, one of which is positively driven, disks carried at the extremities of the shafts and spaced apart, a shaft journaled transversely between the 5 disks, a disk carried rigidly by the shaft in engagement with one of the first mentioned disks and a disk slideable upon the transverse shaft between and in engagement with the other of said first mentioned disks.
- 10 3. In a transmission gear, spaced disks, a shaft journaled between the disks, a disk

carried rigidly by the shaft engaging one of the first mentioned disks and a disk slideable upon the shaft between and engaging the other of said first mentioned disks.

15

In testimony whereof I affix my signature in presence of two witnesses.

LEWIS W. BROWN.
